CONDENSATION PUMP

Robert E. Cortright, Rochester, N. Y., assignor, by
mesne assignments, to Eastman Kodak Company,
Rochester, N. Y., a corporation of New Jersey

Application January 16, 1946, Serial No. 641,479

3 Claims. (Cl. 230—101)

1

My invention relates to an improvement in high vacuum concentric fractionating pumps and in particular to high vacuum pumps in which there are a multiplicity of concentric fractionating columns or boilers.

Such high vacuum pumps are described in and are well known in the prior art as vertical concentric fractionating condensation pumps; see, for instance, patents Hickman U. S. No. 2,211,329, Hickman U. S. No. 2,080,421, and Embree U. S. No. 2,150,676. In such condensation pumps an organic working fluid is heated in a series of concentric boiler compartments and the vapors therefrom are delivered to the jet nozzles through which they then issue, entraining gases from the chamber to be evacuated and condensing on the inside walls of the pump casing and flowing down such walls. The concentric arrangement of the boiler compartments is such that the lowest vapor pressure components of the pump or working fluid, which cannot be vaporized without decomposition, are delivered to a jet nozzle at least once removed from the highest vacuum jet nozzle so that the next lowest vapor pressure components which can be vaporized without appreciable decomposition are delivered to the highest vacuum jet. It has been found, however, that it is difficult to prevent the uncontrolled seepage of the working fluid from one boiler into another and thereby impairing the fractionation in the several boilers and reducing the efficiency of the pumps.

My invention has for its object to provide a means for preventing such uncontrolled seepage or leakage from one boiler into another and thereby to provide more efficient fractionation in the several boilers by controlling the introduction of the pumping fluid into them. Another object is to provide improved high vacuum pumping apparatus. Other objectives will appear hereinafter.

These and other objects are accomplished by my invention which includes a vertical concentric fractionating condensation pump provided with means positioned in or around the boiler or boilers thereof for preventing uncontrolled leakage of pump fluid from one boiler to another.

In the following description I have given several of the preferred embodiments of my invention, but it is to be understood that these are set forth for the purpose of illustration and not in limitation thereof.

In the accompanying drawing, wherein like numbers refer to like parts, I have illustrated one of the preferred embodiments of my invention wherein:

Figure 1 is a vertical section of a high vacuum fractionating pump provided with several concentric boilers or columns embodying the principles of my invention.

Figure 2 is a horizontal section taken on line 2—2 of Fig. 1.

2

Numerals 2 designates a cylindrical pump casing, the base of which is closed by an integral plate 12. The top of the casing 2 is provided with a flange 4 which facilitates connection with the system to be evacuated. The upper end, therefore, represents the high vacuum or intake side of the pump. The low vacuum or exhaust side of the pump is indicated by the conduit 5 which connects with the backing pump (not shown). Numerals 16 and 27 designate approximately concentric cylinders or columns, the base of each of which is in close and liquid-tight contact with an intermediate base plate 3. Concentric cylinders 16 and 27 are each provided with a metal cap or collar, designated respectively as 6' and 6, at their respective bases which fit tightly to the outside of each column. Such cap or collar may, however, be positioned inside the column in a different embodiment of my invention.

Numerals 13, 14, 21 and 23 designate annular jet lips integral with the periphery of the columns 11, 16 and 27, respectively, so as to form high, intermediate and low vacuum jet nozzles. Numerals 22, 24, 26 and 34 designate openings 25 through which vapors issue into the jet nozzles from the spaces between the concentric columns. Numeral 7 designates the annular boiler defined by column 16 and the inside of the pump casing 2 and which supplies working vapor to jet nozzles 13 and 14. Numeral 8 designates an annular boiler which supplies working vapor to jet nozzle 21. Numeral 9 designates an annular boiler which supplies working vapor to jet nozzle 23.

Numeral 10 designates an electrical heating element so positioned in the base of the pump casing between the plate 12 forming the bottom thereof and plate 3 as to heat boiler compartments 7, 8 and 9. Numeral 25 designates copper coils in which water is circulated to cool the casing 2 and assist condensation of the working fluid.

In operating the apparatus illustrated in Fig. 1 an organic pump fluid is introduced into the pump. Flange 4 is connected to the system to be evacuated and conduit 5 is connected to a backing pump in the usual manner. The base plate 3 is then heated by the electrical heating element 10. Vapor produced in boiler section 7 rises in the annular space between column 11 and column 16 and passes through holes 22 and 24 and issues from jet nozzles 13 and 14. The jet entrains gases in known manner which are removed by the backing pump through conduit 5. The jet vapors condense on the walls of casing 2, flow by gravity into the space between 2 and 11 and arrive back into the boiler compartment 7 from which they were derived. The unvaporized liquid in compartment 7 flows in a circular path to opening 18 and into boiler compartment 8. When the liquid arrives in boiler compartment 8 it has traveled in a tortuous path through boiler 7 and has, therefore, been de-

prived of high vapor pressure constituents before passing through opening 18.

In boiler compartment 8 the next lowest below the high vapor pressure constituents are vaporized and pass upwards between concentric columns 16 and 27. These vapors issue through openings 26 and pass out through jet nozzle 21 and are condensed on the wall of casing 2. The condensed liquid flows back into boiler compartment 7. The pump fluid which is not vaporized in boiler compartment 8 passes in a circular or tortuous path to a passage 19 and into boiler compartment 9. Here the lowest vapor pressure components are vaporized and rise and issue through opening 34 and pass from jet nozzle 23. Since this jet is the highest vacuum jet, it is desirable that it be supplied with the best portion of the pump fluid vapors. The vapors issuing from jet 23 are condensed on the walls of casing 2 and flow by gravity back into boiler 7.

It is apparent that efficient fractionation of the pump fluid takes place in the operation of this apparatus. The pump fluid is segregated into components of gradually increasing vapor pressure as in prior constructions but the lowest vapor pressure component is segregated and is not permitted to be vaporized and delivered to the highest vacuum jet. The harmful effects of its decomposition products are thereby avoided.

The feature of causing the pump fluid to pass in a tortuous path through each boiler compartment is also of decided advantage and can be used in fractionating pumps of all types. If the pump fluid is permitted to flow too quickly from one compartment to another it is not efficiently stripped of its lighter constituents and these will be vaporized at a point where they may adversely affect the pumping action. By causing liquid to pass in a tortuous path, removal of all volatile constituents before it reaches the next boiler compartment is assured.

Uncontrolled seepage of such returned pump fluid into boiler designated numeral 9 is prevented by the welding to the bottom of such boiler and the adjacent boiler compartment 8 of metal caps or collars designated numeral 6 which have rims the diameter of which is closely fitted to either the outside or the inside diameter of the base of the concentric fractionating columns. Entrance openings extend through the columns and the caps as designated by numerals 18 and 19 on opposite sides of the columns. Thus not only is seepage prevented by the base of each column being individually and completely sealed off, but my invention also accomplishes a complete circulation in the heating chambers. Due to the thin construction of the sealing cap, the heat remains uniform, if this is desired.

What I claim is:

1. In a fractionating condensation pump of the type having a plurality of concentrically arranged fractionating columns defining at one end thereof a plurality of concentrically arranged boilers adapted to contain pump fluid and intercommunicating in series whereby during operation of said pump said fluid flows in sequence through said boilers in such manner that the high vapor pressure components of the pump fluid exert their pumping action toward a high pressure pumping zone and the low vapor pressure components exert their pumping action toward a low pressure pumping zone of the pump, each said column being apertured in a single localized zone for intercommunicating the boiler defined by said column with the boiler next ad-

jaacent thereto, heat-conducting caps arranged on the ends of said columns and forming bottoms for said boilers, each said cap comprising a plate closing said column and an upturned flange on the periphery of said plate extending upwardly along the column, said caps being sealed to said columns in liquid-tight manner preventing flow of pump fluid between said boilers except through said apertured zones in said columns.

2. In a fractionating condensation pump of the type having a plurality of concentrically arranged fractionating columns defining at one end thereof a plurality of concentrically arranged boilers adapted to contain pump fluid and intercommunicating in series whereby during operation of said pump said fluid flows in sequence through said boilers in such manner that the high vapor pressure components of the pump fluid exert their pumping action toward a high pressure pumping zone and the low vapor pressure components exert their pumping action toward a low pressure pumping zone of the pump, each said column having a single aperture through the wall of the column adjacent the lower end thereof intercommunicating the boiler defined by said column with the boiler next adjacent thereto, the apertures in successive concentric columns being angularly spaced with respect to each other around the periphery of the column whereby pump fluid flowing through the boilers is caused to flow along a tortuous path, heat-conducting caps arranged over the ends of said columns and forming bottoms for said boilers, each said cap comprising a plate closing said column and an upturned flange extending upwardly along the column around the circumferential extent of the column and in close fitting relation thereto, said caps being welded in sealing relation to said columns.

3. In a fractionating condensation pump of the type having a plurality of concentrically arranged fractionating columns defining at one end thereof a plurality of concentrically arranged boilers adapted to contain pump fluid and intercommunicating in series whereby during operation of said pump said fluid flows in sequence through said boilers in such manner that the high vapor pressure components of the pump fluid exert their pumping action toward a high pressure pumping zone and the low vapor pressure components exert their pumping action toward a low pressure pumping zone of the pump, each said column being apertured for intercommunicating the boiler defined by said column with the next adjacent boiler, heat-conducting capping means sealed to the ends of said columns in liquid-tight manner and preventing flow of pump fluid between said boilers except through the apertures in said columns, said capping means comprising plate means closing said columns and upturned flanges on said plate means around the periphery of each said column and extending upwardly along each said column.

ROBERT E. CORTRIGHT.
